UNITED STATES PATENT OFFICE.

ALEXANDER L. VAN ARSDALL, OF KANSAS CITY, MISSOURI.

REMOVABLE SADDLE FOR FIXED DENTAL BRIDGES.

1,091,446.

Specification of Letters Patent. Patented Mar. 24, 1914.

Application filed April 28, 1913. Serial No. 764,103.

To all whom it may concern:

Be it known that I, ALEXANDER L. VAN ARSDALL, a citizen of the United States of America, residing at Kansas City, in the county of Jackson and State of Missouri, have invented a certain new and Improved Removable Saddle for Fixed Dental Bridges, of which the following is a specification.

My invention has for its object the formation of a removable saddle of gold or other suitable material, which, as the resorptive process goes on, may be removed from time to time, and re-adjusted, so as to keep the saddle in proper relation to the alveolar process, and thereby improve the sanitary condition of the bridge work, or the saddle may be removed for the treatment of gum diseases, such as pyorrhea, without disturbing the bridge structure.

The invention consists in the novel parts such as will be first fully described and then specifically pointed out in the claims.

In the drawings, to which reference is now made, and in which like characters of reference indicate corresponding parts: Figure 1 is a broken view of a cast of a maxilla, or human jaw, taken from the lingual side of the alveolar process, with the intervening space shown between the first molar and cuspid, which in the natural teeth form the anchorage for the bridge work. Fig. 2 is a similar view of the cast of the maxilla, as seen in Fig. 1, showing the dummy formed in wax, and the retainer for the removable saddle, in position in the wax dummy. Fig. 3 is a similar view of the cast of the maxilla, as seen in Fig. 2, showing the dummy and the retainer for the saddle secured in position in the dummy, and the lug in position in the socket or retainer, showing the wax form of the removable saddle in position. Fig. 4 is a view of the cast of the maxilla, as seen in Fig. 3, showing the completed bridge, the lug secured to the removable saddle, and the saddle in place upon the alveolar ridge. Fig. 5. is a transverse, vertical, sectional view of the cast of the maxilla, as seen in Fig. 4, taken on the line α , α , on said figure, showing the removable saddle secured to the dummy, also showing in full lines the porcelain facing. Fig. 6. is a view in perspective of the novel retainer for the saddle, and Fig. 7. is a cross-section thereof. Fig. 8. is a view in perspective of the perforate lug for the saddle, which enters the socket or retainer seen in Fig. 6. Fig. 9 is a cross-

sectional view of the lug. Fig. 10. is a detail, enlarged view of the fastening screw for the lug. Fig. 11. is a view in perspective of the saddle, cast from the wax model shown in Figs. 3 and 5. Fig. 12. is a view in perspective of the saddle, with the lug secured thereto. Fig. 13. is a transverse, vertical, sectional view, taken on the line y , y , on Fig. 2. Fig. 14. is an inverted view of the cast dummy, showing the depression for the saddle retainer.

The teeth to which all fixed bridge work is anchored in dental practice, consists of such as are provided with artificial crowns or cast inlay fillings, these forming on each side of the intervening space on the alveolar ridge, from which the natural teeth have been extracted anchorages for the completed bridge. (See Fig. 1.) A wax dummy is then formed between the aforesaid anchorages 15 and 18, and given the proper shape and form. Previous to the making of the wax dummy, I make a retainer, as seen at 20, in Fig. 6, and in cross-section in Fig. 7, for the removable saddle further described, the retainer being made from suitable material, in the main preferably from gold. This retainer, as seen in Fig. 6, consists of a single casting, constituting a receptacle or socket-piece, and as shown is rectangular in form, having a top plate 21, a bottom plate 22, end plates 23, and a closed forward side plate 24, which is inclined downwardly and outwardly, at an angle to the upper surface of the top plate 21, the adjoining portions of the end plates 23 being also inclined at 24° , in like manner.

At the rear portion of the frame, the side in that direction is left open, and extending inwardly through the bottom plate 22, of said retainer or socket, is an opening 25, which extends to the line of the inner surface of the front plate 24 and to within short distances of the lines of the inner surfaces of the ends 23, leaving shelf portions 24 α . Through the adjoining portion of the top plate 21 and the forward side plate 24, at a point intermediate the end plates 23, is made a small opening 26. To the outer surface of said portions of the top-plate 21 and side plate 24 is rigidly connected, by soldering or other suitable means, the nut 27, composed of a different metal from that composing the socket or retainer 20, and preferably of iridio-platinum or gold alloyed with iridio-platinum.

The inner portion of the nut is V-shaped and is fitted to the outer contacting surface of the said top plate 21 and the side plate 24, and having an internal screw-threaded opening 27*, extending around the opening 26, the nut extending a slight distance outwardly, and at an angle to the top plate 21, of said socket or retainer.

A lug 30, as seen in Fig. 8, and in cross-section in Fig. 9, is made or cast from suitable material, preferably from gold, of the size and shape to fit and slide within the opening in the retainer, between the inner surfaces of the ends 23, and upon the shelf 15 portion 24*, of the bottom plate 22, of said socket or retainer, and extends the full distance to the line of the inner surface of the front plate 24. The upper surface 31, of the lug 30, is downwardly inclined, and the lower surface at the ends provided with rabbets 32, which receive and slide upon the shelf-portions 24*, of the bottom plate 22, of the socket or retainer.

The central portion 34 extends downwardly, a considerable distance below the line of the rabbets 32, and forwardly in a horizontal line, the lower surface of the lug 30 being curved or rounded laterally. In the said central portion 34, of the lug, is a cone-shaped opening 35, extending forwardly and through the upper portion of the lug 30, the opening terminating inwardly in a shoulder 37 (see Fig. 9).

The lug 30 is secured at the proper time within the socket 20, by means of a screw 35 having a cone-shaped body or head 39, 38, provided with a nick 40, in its outer end, the cone-shaped portion being fitted to the opening 35, in the lug 30, and the screw 38 fitted to the screw threaded opening 27*, of the nut 27.

After making the wax dummy heretofore referred to, between the anchorages 15 and 18, the wax dummy is removed from the cast 14, and a slot is made in the palatal side of said wax dummy (see Fig. 14), and the retainer is fitted within said slot with the rear or outer surface of the retainer flush with the palatal surfaces of the wax dummy (see Fig. 13), so that the wax dummy with the retainer when returned to cast 14, will appear as in Fig. 2. The wax dummy is removed from the cast 14, and the retainer 30 is removed from the wax dummy. The wax dummy is now cast by any of the common methods of casting. The retainer 20 is then placed in position in the cast dummy 19, and soldered thereto. The dummy is then placed in proper position on the cast 14, and the lug 30 placed within the retainer 20, and the removable saddle formed in wax from an impression made of the cavity beneath the dummy, seen in Fig. 13. The wax form of the saddle is then removed from the cavity, and cast from

gold. The lug 30 is then soldered to the saddle 41, as seen in Fig. 12. The dummy piece 19, with the completed removable saddle, as seen in Fig. 12 in position, is then replaced on the cast 14, between the anchorages 15 and 18, and the dummy soldered to the crown 15 and inlay 18, the dummy, crown and inlay forming what is termed the dental bridge, which is now fitted to the maxilla of the patient.

In case the saddle, thus made, impinges on the alveolar ridge and causes irritation or pain, the saddle may be removed, and the part causing the trouble ground off. In time, as the resorptive process of the alveolar ridge progresses, and it is necessary to readjust the saddle to the alveolar ridge, the saddle may be removed and casting wax placed in position on the saddle and formed to suit the conditions which may exist.

This wax form and the saddle may be invested, as before stated, and gold cast uniting the saddle, or the additional part may be cast separate and soldered on to the saddle and the saddle returned to its place in the bridge.

Instead of casting the saddle, a metal die may be made from an impression of the space between the dummy and the alveolar ridge, and the saddle swaged, and the swaged saddle placed in position and soldered to lug 30.

The retainer, lug and screw are of such form and construction as to admit of universal application and be conformed to the contour of natural teeth. The purpose of the iridio platinum nut 27 is to afford rigidity of threads for holding the screw, and which remain unaffected by the high degrees of heat in the casting or soldering procedure.

Instead of using gold in the making of the saddle, other material suitable for the purpose may be employed.

Such modifications may be employed as are within the scope of the appended claims.

Having fully described my invention, what I now claim as new and desire to secure by Letters Patent is:

1. In fixed dental bridge construction, the combination with the bridge structure of a removable saddle adapted to be adjusted to the alveolar ridge, and means for attaching the saddle to the bridge structure.

2. In dental bridge construction, the means herein described for closing the aperture between the bridge and the alveolar ridge, comprising a saddle adapted to be adjusted to the alveolar ridge, a socket piece on the bridge, and a lug fitting said socket secured to the saddle.

3. In attachments for removable saddles for fixed dental bridges, a socket piece having top and bottom and end members, and a forward side member arranged at an

angle to the said top and bottom members, and a nut secured to the socket piece, said bottom member having an opening extending in the direction of the forward side member.

4. In attachments for removable saddles for fixed dental bridges, a socket piece having top and bottom and end members, and a forward side member arranged at an angle to the said top and bottom members, and a nut secured externally to the top member,

said member having an opening leading to the said nut, and said bottom member having an opening, and sides to said opening extending in the direction of the said forward side member, and a lug fitted to said socket piece.

ALEXANDER L. VAN ARSDALL.
